Primary Examiner—Holly Bayham*Attorney, Agent, or Firm*—Lee, Mann, Smith, McWilliams, Sweeney & Ohlson[57] CLAIM

The ornamental design for a caster wheel, as shown and described.

DESCRIPTION

FIG. 1 is a perspective view of the caster wheel embodying the invention;

FIG. 2 is a front view thereof (the top, bottom and rear views being a mirror image); and,

FIG. 3 is a side view thereof (the outer side being a mirror image).

The broken line showing of a wheel brace is for illustrative purposes only and forms no part of the claimed design.
